SHOE SEWING MACHINE

Frank Bycroft Keall, Leicester, England, assignor to United Shoe Machinery Corporation, Borough of Flemington, N. J., a corporation of New Jersey

Application August 25, 1937, Serial No. 160,737
In Great Britain September 11, 1936

24 Claims. (Cl. 112—34)

This invention relates to sewing machines or mechanisms for use therein, and is particularly, but by no means exclusively, concerned with sewing machines, for sewing together the upper and sole of a boot or shoe by a seam which passes from the outer face of the sole to the inside of the boot or shoe. Machines for this purpose, an example of which is disclosed in the Patent to Richardson No. 710,612 dated October 7, 1902, have hitherto, by reason of peculiarities in their construction, usually been capable of being driven only at comparatively slow speeds. This is apparently due, to a certain extent, to the fact that the mechanisms which operate the stitch forming and work feeding devices tend to develop excessive wear or vibration if it is attempted to run the machines at relatively high speeds.

One of the various objects of the present invention is to provide a sewing machine of novel construction for sewing together an upper and a sole of a boot or shoe by a seam as above referred to, which may be operated at comparatively high speed without excessive vibration or wear developing therein and with the achievement of this object in view there are provided in an illustrative embodiment of the present invention hereinafter described needle operating and work feed mechanisms which are constructed in such manner as to enable them to be driven at comparatively high speed without undue noise and wear of the parts.

In the illustrative embodiment a straight hooked needle reciprocating mechanism is provided which is operated by a crank and by a plurality of links and levers which are so relatively arranged as to allow the needle to move at a comparatively high speed at certain times in a machine cycle and yet to allow the needle to dwell at the top of its stroke while the work is being fed and at the bottom of its stroke while the thread is being placed in the hook of the needle. Also, in the illustrative embodiment the work feeding mechanism is operated by a crank and a plurality of links and levers arranged to operate the feed device of the machine at a relatively high speed and yet to provide a dwell in the movement of the feed device while the needle is penetrating the work.

The nature of the present invention and its several features will become apparent from the following description of the said illustrative embodiment which, for convenience, will be described as being embodied in a sewing machine of the particular kind disclosed by the specification of said Patent No. 710,612.

In the drawings Figure 1 is a right hand side elevation of the said illustrative embodiment; Figure 2 is a front elevation of the illustrative embodiment; Figure 3 is a front elevation, partly

in section, showing particularly part of a work feed mechanism of the illustrative embodiment; Figure 4 is a section on the line IV—IV in Figure 3; Figure 5 is a right hand side elevation, partly in section, of part of a needle actuating mechanism of the illustrative embodiment; Figure 6 is a section on the line VI—VI in Figure 2; Figure 7 is a detail view in front elevation of part of the work feed mechanism; Figure 8 is a section on the line VIII—VIII in Figure 2; and Figure 9 is a front elevation showing some of the parts of the needle actuating mechanism of the illustrative embodiment in the relative positions they occupy when the needle is at the bottom of its movement.

In the said illustrative embodiment a vertical needle-bar 1 is reciprocated upwardly and downwardly by mechanism connecting the needle-bar 1 to a crank pin 3 on a horizontal forwardly and rearwardly extending cam shaft 5 of the machine. The needle bar 1 has secured on its forward side a pin 7, as shown in Figures 2 and 9. Rotatably mounted on the pin 7 is a bell-crank lever 9. One arm 11 of the bell-crank lever 9 extends upwardly from the pivot 7 of the lever and this arm is about twice as long as the other arm 13 of the bell-crank lever which latter arm extends to the left from the pivot 7 of the bell-crank lever more or less perpendicularly to the longer arm 11. The shorter arm 13 of the bell-crank lever is connected by a radius link 15 to a needle adjusting shaft 17 rotatably mounted in bearings on the machine frame. The arm 11 of the bell-crank lever 9 is pivotally connected at its upper end by a pin 19 to the lower end of an arm 21 pivotally mounted on a spindle 23 secured in the machine frame. The arm 21 has pivotally connected to it at 24, one end of a link 25 which at its lower end is pivotally connected at 26 to the upper end of a curved arm 27. The lower end portion of the curved arm 27 is pivoted at its lower end on a shaft 29 carried by a needle adjusting arm 31 which is secured on the needle adjusting shaft 17 and extends towards the left from the needle adjusting shaft 17 to its connection with the curved arm 27. The curved arm 27 has pivoted to it by a pin 33 one end of a link 35, the other end of which is pivotally connected to the crank pin 3 on the cam shaft 5.

As the cam shaft 5 is rotated, the curved arm 27 is swung, by its connection to the crank pin 3, about its pivot shaft 29 in the needle adjusting arm 31. The swinging movement of the curved arm 27 causes, through the link 25 connecting the curved arm and the arm 21 to which the longer arm 11 of the aforesaid bell-crank lever 9 is connected, up and down oscillating movements to the latter arm 21, which arm imparts bodily up and down movements and an

oscillating movement about its pivot pin 7 on the needle-bar to the bell-crank lever 9. The up and down movements of the bell-crank lever 9 are transmitted to the needle-bar 1 by the pin 5 7 on the needle bar on which the bell-crank lever 9 is pivoted. The actual up and down movements of the axis of the bell-crank lever 9 are controlled partly by the arm 21 to which the longer arm 11 of the bell-crank lever 9 is connected and partly by the link 15 to which the 10 shorter arm 13 of the bell-crank lever 9 is connected, the relative arrangement of these parts being such that the pivot pin 7 on the needle bar for the bell-crank lever is constrained to 15 move up and down in substantially a straight line with the result that little, if any, side thrust or twist is imparted to the needle bar 1 during its up and down movements.

The relative lengths and angular dispositions 20 of the parts are such that when the needle-bar 1 is at the top of its upward movement the axes of the cam shaft 5, the crank pin 3 on the cam shaft and the pivot 33 connecting the link 35 to the curved arm 27 are lying substantially 25 on a line extending upwardly and towards the left from the axis of the cam shaft 5 at an angle of about thirty degrees to the horizontal. When the crank pin is in this line, it may be said to be on a dead center and as the crank pin 3 approaches and leaves this line it imparts little or no movement to the needle bar 1, since little or no endwise movement is then imparted to the link 35, which actually dwells at the top of its upward movement during about 90 degrees of 30 rotation of the cam shaft 5. Also when the needle bar is at the top of its upward movement the axis of the shaft 29 on which the curved arm 27 is pivoted and the axes of pivotal connections 26 and 24 all lie substantially on a line passing upwardly and towards the right, at the left hand 35 side of the cam shaft, at an angle of some sixty degrees to the horizontal and as the needle bar approaches and leaves its uppermost position the axis of the pivotal connection 26 between the curved arm 27 and link 25 moves across this line. There are, therefore, in the needle bar actuating mechanism, two toggle-like devices (constituted respectively by the crank 3 and the link 35 connecting it to the curved arm 27 on the one hand and the curved arm 27 and the link 25 connecting the latter to the arm 21 on the other hand) which as the needle-bar is approaching and leaving the top of its upward movement are straightening and breaking and therefore at this time imparting little, if any, movement to the needle bar 1 so that the latter dwells at the top of its upward movement shown in Figure 1.

When the needle bar 1 is at the bottom of its downward movement (Figure 9) the crank pin 3 is on a dead center at the opposite side (i. e. the right hand side) of the cam shaft 5, the axes of the cam shaft 5, crank pin 3, and the pin 33 being again substantially in the same plane, further when the needle bar 1 is at the bottom of 60 its downward movement the axes of the bell crank lever 9, the pin 19 and the pivot 23 of the arm 21 also lie substantially on a line extending through the axis of the cam shaft downwardly and towards the left at an angle of about seventy 65 degrees to the horizontal and also the axes of the bell crank lever 9, the pin connecting the shorter arm 5 of the bell crank lever to its link 15 and the axis of the aforesaid needle adjusting shaft 17 lie substantially on a line extending, just below the cam shaft, at about twenty 70 75

degrees to the horizontal downwardly and towards the right with result that the needle bar dwells at the bottom of its downward movement and this dwell continues during about 90 degrees of rotation of the cam shaft 5. The fact that the needle bar dwells for so long a period at the bottom of its stroke provides ample opportunity for the thread to be laid in the hook of the needle by a whirl of usual type enclosed within the upper end of a work-supporting horn 36. 10

The position heightwise of the needle bar relatively to the work supporting horn 36 of the machine, when the needle bar is at the top of its upward movement, is determined by the heightwise position of a presser bar 37, similar to that referred to as 61, in the Richardson patent. If, when the needle bar 1 is at the top of its upward movement or is approaching or leaving that position the aforementioned needle adjusting arm 31 is swung about the axis of the needle adjusting shaft 17 in a clockwise direction (viewing the machine from the front) the needle bar 1 is, owing to the relative positions of the various parts of the needle bar driving mechanism at these times, moved upwardly. When, however, the needle bar 1 is at the bottom of its downward movement or is approaching or leaving that position, movement of the needle adjusting arm 31 does not, owing to the relative positions of the parts of the needle bar driving mechanism at 20 these times, affect the heightwise position of the needle bar owing to the axes 23, 19 and 7 above mentioned and the axes of the pivots 33, 17 and 29 being also substantially in line at this time. The needle adjusting arm 31 is swung in a clockwise direction by a cam arm 39 pivotally mounted on and depending from the needle adjusting shaft 17 and connected to the arm 31 as hereinafter described. The cam arm 39 has formed on its right hand side a curved face 41 which is engaged by a roll 43 on one arm 45 of a presser bar lever 47 which is secured on the forward end of a horizontal forwardly and rearwardly extending shaft 49 rotatably mounted in the machine frame. Another arm 51 of the presser bar lever 47 is connected to the presser bar 37 by a member 53 pivoted at 55 to the arm 51 and having pivoted on it a block 57 which is engaged by a recess formed in the presser bar. The member 53 has threaded in it two screws 59 which engage the arm 51 and which may be adjusted to swing the member 53 about the pivot 55 and thus raise or lower the presser bar relatively to the arm 51. Since the heightwise position of the needle at the top of its stroke is controlled by the heightwise position of the presser, adjustment of the presser bar by means of the screws 59 varies the heightwise position of the needle bar at the top of its stroke relatively to the work. The presser bar 37 is urged downwardly by a spring (not shown) coiled round the presser bar lever shaft 49. The aforesaid cam arm 39 is connected to the needle adjusting arm 31 in such a manner, as will hereinafter appear, that when the presser bar 37 is lifted by means of treadle operated mechanism to allow work to be placed on or removed from the work-supporting horn 36 of the machine, at which time the needle-bar 1 is in its fully raised position, the needle adjusting arm 31 is swung in a clockwise direction, owing to swinging movement of the roll 43 on the presser bar lever 47 towards the left, and the needle bar 1 is raised. When the presser bar 37 is allowed to descend again, on release of the treadle, and is positioned height- 50 55 60 65 70 75 80 85 90 95 100 105 110 115 120 125 130 135 140 145 150 155 160 165 170 175 wise by the work, the position of the needle bar, when at the top of its upward movement, is determined, owing to the consequent movement of the said roll 43 towards the right, by the height-wise position of the presser bar according to the thickness of the work on the work supporting horn 36 of the machine. The mechanism therefore acts to cause the needle, at the upper limit of its movement, to occupy a constant position 10 above the upper face of the work whatever be the thickness of the latter.

The presser bar lever 47 and the needle adjusting arm 31 are connected together by a stirrup member 61 which has formed in it a slot 15 63. The right hand end of the slot 63 normally engages a pin 65 secured in the arm 45 of the presser bar lever 47. The opposite end of the stirrup member 61 has threaded into it a screw 20 67 which projects into the slot 63 and extends lengthwise thereof. When the presser foot 69 is pressing against the work the screw 67 is in engagement with a rectangular block 71 which is pivoted on a plate 73 secured on the needle adjusting arm 31 and engages in the slot 63 in 25 the stirrup member 61, this block 71, together with the pin 65 on the presser bar lever arm 45 supporting the stirrup member 61. The pin 65 on the presser bar lever arm 45 at this time engages the right end of the slot 63. The stirrup member 61 ensures that, after the presser bar lever 47 and needle adjusting arm 31 have been moved simultaneously by the raising of the presser bar 37 by the treadle, the needle adjusting arm 31 will be returned when the presser bar 35 is allowed to descend again and the slot 63 in the stirrup member 61 allows the presser bar lever 47 to move relatively to the needle adjusting arm 31 when the presser bar is raised automatically during each machine cycle to allow the work to be fed.

When the presser bar is raised during the operation of the machine to allow the work to be fed, the needle bar 1 is approaching the top of its upward movement and unless means are provided to prevent the needle bar from being given a small upward movement by the lifting of the presser bar the needle bar will be given an unnecessary and undesirable upward movement during each cycle of the machine. In the 45 illustrative embodiment means is provided which allows the needle bar 1 to be lifted when the presser bar 37 is raised by the treadle operated means but prevents the needle bar 1 from being lifted when the presser bar 37 is raised during the operation of the machine to allow the work to be fed. The said means comprises a connection between the aforesaid cam arm 39 and the aforesaid needle adjusting arm 31 which connection acts when the presser bar 37 is raised 50 by the treadle to cause the cam arm 39 and the needle adjusting arm 31 to move together as a unit so that the needle bar is then raised. When the presser bar 37 is raised during the operation of the machine to allow the work to be fed the connection between the cam arm 39 and the needle adjusting arm 31 is caused to 55 collapse with the result that the cam arm 39 moves relatively to the needle adjusting arm 31 without moving the latter so that the needle bar 60 is not then raised. The connection between the cam arm 39 and the needle adjusting arm 31 comprises a comparatively short more or less vertical arm 75 (Figure 5) which has slidably mounted in its upper end a ball-ended stud 77, 65 the ball-end of which is rotatably mounted in

a seating in the cam arm 39. The lower end of the arm 75 is secured to the forward part of a rearwardly and upwardly inclined shaft 79 positioned below the needle adjusting shaft 17. The inclined shaft 79 has rotatably mounted on its forward end a rectangular block 81 which engages a substantially vertical guideway 83 (Figure 2) formed between lugs extending rearwardly from the plate 73 on the needle adjusting arm 31. The forward end of the inclined shaft 10 79 is supported by the short arm 75 (Figure 5) secured on the forward part of the shaft. The rear portion of the inclined shaft 79 is rotatably mounted in the lower end of an arm 85 secured on and depending from the needle adjusting shaft 17. The rear end of the inclined shaft has secured on it an upwardly extending arm 87 which has secured in its upper end a horizontal ball-ended pin 89 on the ball-end of which at the rear of the arm is pivoted one end 20 of a link 91. The other end of the link 91 is pivotally connected by a universal coupling to a presser cam lever 93 (corresponding to the lever referred to as 86 in said patent) which has on it a cam roll 95 which enters a cam groove in a 25 cam, indicated at 97, secured on the cam shaft 5. The presser cam lever 93, as described in said patent, is coupled during each cycle of the machine, to the presser bar and is operated to cause the presser bar to be raised during each 30 cycle while the work is being fed. When the machine stops, at which time the presser bar may be raised by the treadle operated means, the presser cam lever 93 is so positioned by its cam that the axis of the universal coupling connecting the link 91 to the arm 87 on the inclined shaft 79 is in alignment with the axis of the needle adjusting shaft 17. When, therefore, the needle adjusting shaft 17 is rotated in a clockwise direction through the presser bar lever 47, cam arm 39, arm 75, shaft 79 and arms 31 and 85 by the raising of the presser on depression of the treadle, the inclined shaft 79 is, by reason of its connection to the needle adjusting shaft 17, carried bodily round the needle adjusting shaft 17, thus rocking the needle adjusting arm 31, without being rotated about its own axis, and the needle bar, then in its fully raised position, will be raised further. When the presser bar is allowed to descend on to the work its heightwise position and the heightwise position of the needle when at the top of its upward movement are controlled by the work. When the presser cam lever 93 is actuated by its cam 97 during the operation of the machine to raise the presser bar while the work is being fed the aforesaid cam arm 39 is, by its connection (including the arm 45 and roll 43) to the presser bar, swung about the needle shaft 17 in a clockwise direction. At the same time that the presser cam lever 93 raises the presser it also, by its connection thereto rotates the inclined shaft 79 about its own axis and moves, through the pin 77, the cam arm 39, which is freely pivoted on the needle adjusting shaft 17, in advance 55 of the aforesaid roll 43 on the arm 45 of the presser lever 47 without moving the arm 31 and needle adjusting shaft 17.

The needle adjusting shaft 17 has secured to it an arm 99 which extends from the needle adjusting shaft 17 over the cam shaft 5 towards the right hand side of the machine and which has pivoted to its right hand end by a pin 101 a link 103 which extends downwardly from the arm and is pivotally connected at its lower end 75

to the upper end of a vertical ratchet bar 105 slidingly mounted in the machine frame. The ratchet bar 105 on its rear face has formed on it a series of ratchet teeth 107 which are engaged 5 by the upper end of a pawl 109 pivoted between its ends on a horizontal stud 111 secured in the machine frame. When the pawl 109 is in engagement with one of the ratchet teeth 107 downward movement of the ratchet bar 105 is 10 positively prevented and, owing to the connection of the ratchet bar to the needle adjusting shaft 17, rotation of that shaft in a clockwise direction and consequent raising of the needle-bar 1 are prevented. The lower end of the pawl 109 has pivotally connected to it the forward end of a link 113 which, at its rear end, is pivotally connected to a cam lever 115 (similar to the lever referred to as 97 in said patent) which as described in said specification causes the 15 presser bar 37 to be connected to its lifting cam lever 93 during the operation of the machine. When the cam lever 115 is moved by its cam, indicated at 117 Figure 5, on the cam shaft 5 in a direction to cause the presser bar 37 to be connected to its lifting cam lever 93 prior to the raising of the presser bar, the pawl 109 is moved into engagement with one of the ratchet teeth 107. The ratchet bar 105 has secured in its right hand side a horizontal pin 119 which is engaged 20 by a substantially horizontal recess 121 formed in the rear end of a substantially horizontal lever 123 pivoted on a horizontal stud 125 secured in the machine frame. The forward end of the lever 123 is rounded and enters a recess formed in 25 the right hand side of a vertical plate 127 (Figures 1 and 2) at the front of the presser bar 37. The vertical plate 127 is guided vertically by a stud 129 (corresponding to the screw-pin referred to as 66 in said patent) secured in the machine frame and passing through a vertical slot 131 in the upper end of the plate and a stud 133 (Figure 6) secured in the presser bar which passes 30 through another vertical slot 135 in the plate near its lower end.

The vertical plate 127 has rotatably mounted in it, near its lower end a horizontal extending pin 137. The pin 137 extends rearwardly from the plate and passes through a vertical slot 139 in the presser bar 37. The pin 137 has secured at 35 its rear end a rectangular block 141 (Figures 2 and 7) which enters an inclined guideway 143, extending downwardly towards the left, formed in a feed point carrier 145. The feed point carrier 145 lies just behind the presser bar 37 and is guided by the rectangular block 141 and by a pin 147 extending rearwardly from the presser bar 37 which is engaged by an open ended slot 149 in the upper end of the feed point carrier 145. Freely pivoted on the lower end of the feed point 40 carrier, on a pin 151, is a depending feed point arm 153 in the lower end of which a feed point 45 155 is secured, the relative positions of the feed point 155 and the presser bar 37 being similar to those indicated in the patent aforementioned.

The feed point arm 153 is normally drawn towards 50 the right into contact with the presser foot 69 by a tension spring 157 connected at one end to the feed point arm 153 and at the other end to the presser bar 37. The feed point arm 153 has 55 secured in it between its pivot and its feed point a rearwardly extending pin 159, to which one end of the spring 157 is connected, and the feed point carrier 145 has formed in its left hand side near its lower end a recess 161 arranged, 60 during movement of the feed point carrier 145 in

the direction of work feed, to engage the pin 159. When the lower end of the feed point carrier 145 is moved towards the left, by mechanism hereinafter described, in a direction to feed the work, the lower end of the feed point carrier is guided 5 downwardly and towards the left by the aforesaid block 141 in the inclined guideway 143 in the feed point carrier 145. During the early part of the movement of the feed point carrier 145, the feed point arm 153 is held by the aforementioned 10 spring 157 against the presser foot 69 and the feed point descends more or less vertically into the work. When the recess 161 in the feed point carrier 145 engages the pin 159 in the feed point arm 153, the feed point arm 153 and feed point 15 155 then engaging in the work move with the feed point carrier 145 and the feed point feeds the work, the feed point carrier 145 being guided by the block 141 on the vertical plate and the aforesaid pin 147 on the presser bar 37. The block 20 141 and the pin 147 are so relatively arranged that when the feed point 155 is feeding the work its lower end moves substantially horizontally towards the left. At the time in the machine cycle when the presser bar 37 is raised to allow 25 the work to be fed by the feed point the aforesaid pawl 109 is in engagement with the ratchet teeth 107 on the ratchet bar 105 and the feed point carrier 145 is, by reason of its connection with the ratchet bar, prevented from being moved 30 upwardly with the presser bar, thus preventing the feed point from rising from the lowest position which it reached in digging into the work preparatory to feeding it. Since the ratchet bar 105 is, as hereinbefore described, secured on the 35 aforesaid needle adjusting shaft 17, the needle shaft is prevented from being rotated in a clockwise direction and the needle-bar is therefore prevented, by the pawl and ratchet teeth, from being raised by the lifting of the presser bar 40 which takes place to allow the work to be fed by 45 the feed point.

The pawl 109 preferably engages the ratchet teeth 107 during the greater part of the machine cycle, being released therefrom after the work 45 is fed only about long enough to allow the needle mechanism to accommodate itself to the heightwise position of the presser after the latter has been allowed to descend on to the work after the work has been fed. The pawl and ratchet teeth therefore prevent any tendency there may 50 be to overthrow during the movement of the needlebar, at other times in the machine cycle, due to the momentum of the parts.

The aforesaid mechanism for moving the feed 55 point carrier 145 towards the left to feed the work comprises a crank and a plurality of links and levers the shafts and pivot pins of which all extend horizontally forwardly and rearwardly of the machine and the mechanism includes a substantially horizontal link 171 which at its right hand end is connected to the pin 151 and at its left hand end is pivotally connected to the lower end of one arm of a bell-crank lever 173 which is pivoted on a pin 175 secured in a depending arm 177 of a second bell-crank lever 179. The bell-crank lever 173 has an upwardly extending arm 181 the upper end of which lies at a lower level than the cam shaft 5 aforementioned and the upper end of the arm has mounted on it a cam roll 70 183 which is held by a spring against the underside of a cam 185 on the forward end of the cam shaft 5, this cam serving to rock the bell-crank lever 173 about its pivot 175 on the bell-crank lever 179. The bell-crank lever 179 is pivoted 75

on the forward end of a shaft 187 mounted in the machine frame and has a second arm 189 (Figure 3) which extends towards the right from the hub of the lever. The arm 189 of the bell-crank lever 179 has pivoted to its right hand end one end of a link 191 which extends upwardly and towards the right and at its upper end is pivotally connected to one end of a feed adjusting lever 193. The feed adjusting lever 193 extends upwardly and to the left from its connection to the link 191 and at its left hand end is pivoted on a crank pin 195 which may be adjusted to alter the position in the machine of the left hand end of the feed adjusting lever 193 and may be locked in its adjusted position so that the crank pin 195 provides a fixed but adjustable pivot for the left hand end of the feed adjusting lever 193. The crank pin 195 extends forwardly from an arm 196 secured on a crank shaft 197, rotatably mounted in the machine frame, which is angularly adjustable to vary the position of the crank pin 195 in the machine frame. The crank shaft 197 has secured on its rear end an arm 199 (Figure 4) by which the crank shaft may be rotated. The arm 199 extends towards the right hand side of the machine and its right hand end carries a clamping device by which the arm may be clamped in adjusted position to a plate 201 secured on the machine frame. The clamping device comprises a bolt 203 extending through the arm 199 and through a block 205. The bolt has on one end of it a head 207 which engages the block 205 and on its other and threaded end a hand nut 209 by means of which the block 205 and arm 199 may be clamped against the plate 201. The hand nut 209 may be used to swing the arm 199 and crank pin 196 upwardly or downwardly. The feed adjusting lever 193 is pivotally connected at 211, between its ends, to one end of a link 213 which extends downwardly and to the left from the feed adjusting lever and at its other end is pivotally connected, at 215, to a depending arm of a bell-crank lever 217 which is secured on a shaft 219 rotatably mounted in the machine frame. The other arm of the bell-crank lever 217 extends upwardly and to the left from the hub of the lever and has pivotally connected to its upper end, at 221, one end of a link 223 the other end of which is pivotally connected, at 225, to the right hand end of a crank lever 227. The left hand end of the crank lever 227 is pivoted on a crank 229 on the cam shaft 5 and between its ends the crank lever is pivotally connected at 231, to the upper end of a radius arm 233 which serves to control the direction of movement of the right hand end of the crank lever 227 as the cam shaft rotates. The radius arm 227 is secured at its lower end on a shaft 235 which is rotatably mounted in the machine frame below and just to the right of the cam shaft. As the cam shaft 5 rotates the right hand end of the crank lever 227 is caused, by the crank 229 and radius arm 233, to move in a more or less elliptical path, indicated by the dot-and-dash line 237 Figure 3, one side of which is during the movement of the right hand end of the crank lever 227 along it concentric to the pivot 221 connecting the link 223 to the bell-crank lever 217 and therefore during this part of the movement of the right hand end of the crank lever 227 no endwise movement is imparted to the link 223 and no feed movement is imparted to the feed point through the crank lever 227, the feed point dwelling, after it has become embedded in the work through the rock-

ing of the bell-crank lever 173 both while the needle is piercing the work and while it is moving upwardly with a loop of thread in its hook. When the right hand end of the crank lever 227 is moving along the opposite side of its elliptical path 237 it imparts appreciable endwise movements to the link 223 connected to it and feeding and return movements are, during this part of the movement of the crank lever 227, given to the feed point. If the crank pin 195, on which the feed adjusting lever 193 is pivoted, is adjusted in such a manner as to move the pivot 211 connecting the feed adjusting lever 193 and the link 213 nearer to or further away from the shaft 219 to which the bell-crank lever 217 is secured, such adjustment varies the angular relationship between the depending arm of the bell-crank lever 217 and the link 213 and varies the amount of movement imparted to the feed point.

The dot and dash line *a* in Figure 3 indicates the path of movement of the axis of the pivot 211 when the crank pin 195 is adjusted, in a counter-clockwise direction, to reduce the length of feeding movement of the work. The line *b* indicates the position of the axis of the pivot 211 at the end of the different lengths of feeding movement of the feed point and the lines *c* of different length indicate the distances the axis moves during different lengths of feeding movement of the feed point.

The cam 185 on the cam shaft 5 which actuates the bell-crank lever 173 causes the feed point 155, after the work has been fed and the feed point has been returned towards the right, to be moved downwardly into engagement with the work and to be held there during the aforementioned dwell of the feed point.

During the feed of the work, the bell-crank lever 173 is carried bodily towards the left by the swinging movement of the bell-crank lever 179 and the cam roll 183 on the bell-crank lever 173 moving idly under its cam. As the feed point is reaching the end of its return movement towards the right, during which it trails along the work and is being thus moved by the crank 229 and link mechanism while the cam roll 183 on the bell-crank lever 173 moves to the right with the bell-crank lever 179 idly beneath the cam, the feed point carrier 145 is moved upwardly by the engagement of the inclined guide-way 143 in the feed point carrier with the block 141 on the aforesaid vertical plate 127 and the feed point 155 is raised above the work. The part of the movement of the feed point carrier 145 which takes place while the latter is being raised is effected by the conjoint action of the crank 229 and the cam 185 which act simultaneously to move the feed point carrier 145 towards the right. After the feed point carrier 145 has been moved to the right far enough to raise the feed point above the work the mechanism operated by the crank 229 dwells as aforesaid and the cam 185 moves the feed point carrier sufficiently far towards the left to cause the feed point to move downwardly into engagement with the work in readiness again to feed the work. The cam operated mechanism and the bell-crank lever 173 then dwell while the needle passes through the work and rises therefrom with a loop of thread in its hook.

A sewing machine provided with the mechanisms hereinbefore described for actuating and controlling the needle bar and work feed point

is capable of being operated at comparatively high speed without undue noise or vibration, the raising of the presser foot independently of the feed point ensuring that the feed point firmly engages 5 with the work and feeds the work the full distance through which the feed point moves during its feeding movement.

In the illustrative embodiment a cast-off mechanism is provided which is substantially similar 10 to the cast-off mechanism described in Patent No. 1,713,186 to Bernard T. Leveque dated May 14, 1929, and operates in a similar manner. The cast-off 241 is mounted to slide in a vertical groove in the right hand side of the needle bar 15 and is secured at its upper end in a collar 243 mounted to slide vertically on the needle bar between blocks 245, 247 secured on the needle bar 1 above and below the collar 243. The collar 243 has secured in it a forwardly extending pin 20 on which is rotatably mounted a roll 249 which as the needle bar moves up and down passes between the upper inwardly inclined ends of a pair of levers 251, 253 similar to the levers referred to as 72, 74 in the latter specification 25 which are normally urged towards each other by a spring 255 similar to the spring referred to as 76 in said specification. In the illustrative embodiment the levers 251, 253 are pivoted on a block 257 which is pivoted on a horizontal forwardly and rearwardly extending stud 259 secured 30 in a bracket 261 which is fixed to the machine frame. The stud 259 is positioned a little below and centrally between the pivots 263, 265 of the levers 251, 253. The block 257 has extending 35 to the left from it an arm 267 on which is secured a blade spring 269 which extends towards the left from the block and its left hand end extends between two pins 271, one above and the other below the spring, which are secured in an 40 arm 273 projecting from the bracket 261 and which hold the left hand end of the spring from upward or downward movement but allow it to move lengthwise between them. The spring 255 is arranged to normally hold the levers in a 45 central position with respect to the needle bar. The pivotal mounting of the block 257 on which the levers 251, 253 are pivoted and the blade spring 269 allow the levers to rock bodily to the right or left of the needle bar should it, during 50 its upward or downward movement, be turned about its axis and thus enables the roll 249 on the collar 243 to bear equally upon the inclined upper faces of the levers.

The nature and scope of the invention having 55 been indicated, and a machine embodying the several features of the invention having been specifically described, what is claimed is:

1. A shoe sewing machine having, in combination, stitch forming devices including a straight hook needle, a rotating crank, lever and link connections between the crank and needle for actuating the needle from the crank, a support upon which one of the levers is mounted movable to vary the stroke of the needle, a presser foot, 60 connections between the support and the presser foot for adjusting the support for different thicknesses of work, mechanism for lifting the presser foot during each stitch forming cycle, and means actuated by said mechanism for rendering the 65 connections between the presser foot and said support inoperative to move the support as the presser foot is lifted by said mechanism.

2. A shoe sewing machine having, in combination, stitch forming devices including a straight hook needle, a rotating crank, lever and link 70 connections between the crank and needle for actuating the needle from the crank, a support upon which one of the levers is mounted movable to vary the stroke of the needle, a presser foot, and connections between the support and the presser foot for adjusting the support for different thicknesses of work comprising a presser foot bar, a 75 lever having one end engaging the support, and a block adjustably mounted on the other end of the lever and engaging the presser foot bar.

connections between the crank and needle for actuating the needle from the crank, a support upon which one of the levers is mounted movable to vary the stroke of the needle, a presser foot, 5 connections between the support and the presser foot for adjusting the support for different thicknesses of work, mechanism for lifting the presser foot during each stitch forming cycle, and means for preventing movement of said support by the presser foot as the presser foot is lifted by said 10 mechanism.

3. A shoe sewing machine having, in combination, stitch forming devices including a straight hook needle, a rotating crank, lever and link connections between the crank and needle for 15 actuating the needle from the crank, a support upon which one of the levers is mounted movable to vary the stroke of the needle, a presser foot, connections between the support and the presser foot for adjusting the support for different thicknesses of work, and for moving the support to 20 raise the needle when the presser foot is raised for the removal or insertion of work, mechanism for lifting the presser foot during each stitch forming cycle, and means for preventing movement of said support by the presser foot as the 25 presser foot is lifted by said mechanism.

4. A shoe sewing machine having, in combination, stitch forming devices including a straight hook needle, a rotating crank, lever and link connections between the crank and needle for actuating the needle from the crank, a support upon which one of the levers is mounted movable to vary the stroke of the needle, a needle adjusting 30 shaft to which the support is secured, an actuating arm pivotally mounted on the needle adjusting shaft, an arm rigidly mounted on the shaft, a rotatable shaft supported in the rigidly mounted arm, and in the support, an arm rigid with the rotatable shaft and pivotally connected 35 with the actuating arm, a presser foot, connections from the presser foot for moving the actuating arm to adjust the needle adjusting shaft and support for different thicknesses of work, mechanism for lifting the presser foot during 40 each stitch forming cycle, and means actuated by said mechanism for rotating said rotatable shaft to swing the actuating arm on the adjusting shaft and thereby prevent an adjustment of the needle 45 adjusting shaft and support as the presser foot 50 is lifted.

5. A shoe sewing machine having, in combination, stitch forming devices including a straight hook needle, a rotating crank, lever and link connections between the crank and needle for actuating the needle from the crank, a support upon 55 which one of the levers is mounted movable to vary the stroke of the needle, a presser foot, and connections between the support and the presser foot for adjusting the support for different thicknesses of work, comprising a presser foot bar, a lever having one end engaging the support, and a block adjustably mounted on the other end of the lever and engaging the presser foot bar.

6. A shoe sewing machine having, in combination, stitch forming devices including a straight hook needle, a rotating crank, lever and link connections between the crank and needle for actuating the needle from the crank, a support upon which one of the levers is mounted movable to 60 vary the stroke of the needle, a presser foot, and connections between the support and the presser foot for adjusting the support for different thicknesses of work comprising a presser foot bar, a lever having one end engaging the support, and 65

- means adjustably connecting the presser foot bar and the other end of the lever.
7. A shoe sewing machine having, in combination, stitch forming devices including a straight hook needle, a single rotating crank, and connections between the crank and needle for actuating the needle comprising levers and links arranged to form two toggles, one of which is substantially straight when the needle is at the top of its stroke and while the crank is passing over one dead center, and the other of which is substantially straight when the needle is at the bottom of its stroke and the crank is passing over the other dead center.
- 15 8. A shoe sewing machine having, in combination, stitch forming devices including a straight hook needle, a rotating crank, and connections between the crank and needle for actuating the needle comprising a lever, a link connecting the crank and lever, a bell crank, a link connecting the lever and bell crank and forming a toggle with the lever, and a link connecting the bell crank to the needle and forming a toggle with the bell crank, the first mentioned toggle being straightened when the needle is at the top of its stroke, and while the crank is passing over one dead center and the other toggle being straightened when the needle is at the bottom of its stroke and while the crank is passing over the other dead center.
9. A shoe sewing machine having, in combination, stitch forming devices including a straight hook needle, a horn arranged to extend within the shoe, means for actuating the needle to pierce and withdraw from the work, a presser foot, a feed point carrier movable back and forth in the line of feed, a feed point pivotally mounted on the carrier and arranged to slide on the presser foot into engagement with the work at the beginning of the forward movement of the carrier and out of engagement with the work at the end of the backward movement of the carrier, and a support for the feed point carrier separate from the presser foot arranged to permit the presser foot to be lifted without lifting the carrier.
10. A shoe sewing machine having, in combination, stitch forming devices, a straight hook needle, a horn arranged to extend within the shoe, means for actuating the needle to pierce and withdraw from the work, a presser foot, a feed point carrier movable back and forth in the line of feed, a feed point pivotally mounted on the carrier and arranged to slide on the presser foot into engagement with the work at the beginning of the forward movement of the carrier and out of engagement with the work at the end of the backward movement of the carrier, and means for supporting the feed point carrier while permitting a lifting movement of the presser foot without lifting the carrier.
11. A shoe sewing machine having, in combination, stitch forming devices, a straight hook needle, a horn arranged to extend within the shoe, means for actuating the needle to pierce and withdraw from the work, a presser foot, a feed point carrier movable back and forth in the line of feed, a feed point pivotally mounted on the carrier and arranged to slide on the presser foot into engagement with the work at the beginning of the forward movement of the carrier and out of engagement with the work at the end of the backward movement of the carrier, mechanism for actuating the feed point carrier and presser foot arranged to cause the feed point to

enter the work before the presser foot is raised and to raise the presser foot while the feed point is engaged with the work without raising the feed point carrier.

12. A shoe sewing machine having, in combination, stitch forming devices including a straight hook needle, a horn arranged to extend within the shoe, means for actuating the needle to pierce and withdraw from the work, a presser foot, a feed point carrier movable back and forth in the line of feed, a feed point mounted on the carrier, means comprising a cam for actuating the feed point carrier to cause the feed point to engage the work, and means comprising a crank for actuating the feed point carrier to cause the feed point to feed the work.

13. A shoe sewing machine having, in combination, stitch forming devices including a straight hook needle, a horn arranged to extend within the shoe, means for actuating the needle to pierce and withdraw from the work, a presser foot, a feed point carrier movable back and forth in the line of feed, a feed point mounted on the carrier, and means for actuating the feed point carrier comprising a radius arm, a crank actuated lever pivoted on the radius arm, a crank engaging one end of the lever, a link pivotally connected to the other end of the lever, and an actuating lever to which the link is connected, said parts being arranged to cause a to-and-fro oscillation of the actuating lever during a portion of the crank rotation, and during the remainder of the crank rotation to maintain the actuating lever stationary.

14. A shoe sewing machine having, in combination, stitch forming devices including a straight hook needle, a horn arranged to extend within the shoe, means for actuating the needle to pierce and withdraw from the work, a presser foot, a feed point carrier movable back and forth in the line of feed, a feed point mounted on the carrier, and means for actuating the feed point carrier comprising a radius arm, a crank actuated lever pivoted on the radius arm, a crank engaging one end of the lever, a link pivotally connected to the other end of the lever, and an actuating lever to which the link is connected, said parts being arranged to cause a to-and-fro oscillation of the actuating lever during a portion of the crank rotation, and during the remainder of the crank rotation to maintain the actuating lever stationary, connections from the actuating lever to the feed point carrier, and means for adjusting said connections to vary the feeding movement of the feed point carrier.

15. A shoe sewing machine having, in combination, stitch forming devices including a straight hook needle, a horn arranged to extend within the shoe, means for actuating the needle to pierce and withdraw from the work, a presser foot, a feed point carrier movable back and forth in the line of feed, a feed point mounted on the carrier, and means for actuating the feed point carrier comprising a radius arm, a crank actuated lever pivoted on the radius arm, a crank engaging one end of the lever, a link pivotally connected to the other end of the lever, and an actuating lever to which the link is connected, said parts being arranged to cause the pivot connecting the crank actuated lever and the link during a portion of the crank rotation to be moved back and forth across the line joining the pivot of the crank actuated lever, and the pivot connecting the link with the actuating lever in a path to impart a to-and-fro oscillation to the actuating lever and

during another portion of the crank rotation to be moved in a path concentric to said last mentioned pivot to maintain the actuating lever stationary.

- 5 16. A shoe sewing machine having, in combination, stitch forming devices including a straight hook needle, a horn arranged to extend within the shoe, means for actuating the needle to pierce and withdraw from the work, a presser 10 foot, a feed point carrier movable back and forth in the line of feed, a feed point mounted on the carrier, and means for actuating the feed point carrier comprising a pivotally mounted feed adjusting lever, connections from said lever to 15 the feed point carrier, an actuating lever, a link connecting said levers, and means for adjusting the pivot of the feed adjusting lever to change the relative position of the link and actuating lever.
- 20 17. A shoe sewing machine having, in combination, stitch forming devices including a straight hook needle, a horn arranged to extend within the shoe, means for actuating the needle to pierce and withdraw from the work, a presser 25 foot, a feed point carrier movable back and forth in the line of feed, a feed point mounted on the carrier, a lever, connections from the lever to the feed point carrier, a support on which the lever is mounted, a cam for actuating the lever 30 to cause the feed point to engage the work, and a crank and connections for actuating the support with the lever to cause the feed point to feed the work.

- 35 18. A shoe sewing machine having, in combination, stitch forming devices including a straight hook needle, a horn arranged to extend within the shoe, means for actuating the needle to pierce and withdraw from the work, a presser foot, a feed point carrier movable back and forth in 40 the line of feed, a feed point mounted on the carrier, and means for actuating the feed point carrier comprising an actuating lever, a crank, a link pivoted at one end to the lever, and connections between the crank and the link arranged 45 to cause the other end of the link, during a portion of the crank rotation, to be moved back and forth in a path concentric with the pivotal connection of the link with the actuating lever, and during another portion of the crank rotation to 50 be moved back and forth in a path to impart a to-and-fro oscillation to the actuating lever.

- 55 19. A shoe sewing machine having, in combination, stitch forming devices including a straight hook needle, a horn arranged to extend within the shoe, means for actuating the needle to pierce and withdraw from the work, a presser foot, a feed point carrier movable back and forth in 60 the line of feed, a feed point mounted on the carrier, a presser foot bar, a support for the feed point carrier mounted to slide on the presser foot bar towards and from the horn, connections between the presser foot and the support for regulating the position of the support with 65 relation to the horn, and means for preventing movement of the support when the presser foot bar is moved away from the horn to allow the work to be fed.

- 70 20. A shoe sewing machine having, in combination, stitch forming devices including a straight hook needle, a horn arranged to extend within

the shoe, a rotating crank, lever and link connections between the crank and needle for actuating the needle from the crank, a support upon which one of the levers is mounted movable to vary the stroke of the needle, a presser-foot, 5 connections between the support and the presser-foot for adjusting the support for different thicknesses of work, a presser foot bar, a feed point carrier movable back and forth in the line of feed, a feed point mounted on the carrier, a support for the feed point carrier mounted to slide on the presser-foot bar towards and from the horn, and connections between said supports for regulating the position of the feed point carrier support with relation to the horn. 15

21. A shoe sewing machine having, in combination, stitch forming devices including a straight hook needle, a rotating crank, lever and link connections between the crank and needle for actuating the needle from the crank, a support upon which one of the levers is mounted movable to vary the stroke of the needle, a presser foot, connections between the support and the presser foot for adjustably limiting the movement of the support in one direction to adjust the support for different thicknesses of work, and means acting during a portion of each stitch forming cycle to lock the support against movement in the opposite direction. 20

22. A shoe sewing machine having, in combination, stitch forming devices including a straight hook needle, a rotating crank, lever and link connections between the crank and needle for actuating the needle from the crank, a support upon which one of the levers is mounted movable to vary the stroke of the needle, a needle adjusting shaft to which the support is secured, a presser foot, connections between the shaft and the presser foot for adjustably limiting the rotation of the shaft in one direction, a bar connected to the shaft, and cam actuated means for locking the bar against movement during a portion of each stitch forming cycle to limit the rotation of the shaft in the opposite direction. 30

23. A shoe sewing machine having, in combination, stitch forming devices including a straight hook needle, a cast-off movable with the needle and having a limited independent movement, a pin connected to the cast-off, yielding members connected to move in unison towards and from each other between which the pin passes during the needle movement and by which the cast-off is moved with relation to the needle, and a block upon which said members are mounted, said block being mounted for yielding movement 40 transversely of the needle movement to cause the pin to bear equally upon said members. 45

24. A shoe sewing machine having, in combination, stitch forming devices including a straight hook needle, a cast-off movable with the needle 60 and having a limited independent movement, a pin connected to the cast-off, yielding members between which the pin passes during the needle movement and by which the cast-off is moved with relation to the needle, a pivotally mounted 65 block upon which said members are mounted, and a spring acting on the block to hold said members yieldingly in the path of said pin. 70
